SIGNAL DEVICE FOR FLUID CURRENT METERS

Willard L. Egy, Troy, N. Y., assignor to W. & L. E. Gurley, Troy, N. Y., a corporation of New York

Application July 18, 1939, Serial No. 285,186

3 Claims. (Cl. 177—311)

This invention relates to signal devices of the type used in fluid current meters and like mechanisms to count the revolutions of the meter. Basically, the operation is to count successive 5 audible signals produced by the rotation of the meter shaft.

In current meters of the so-called "Price" type, it is known practice to have the meter shaft drive a secondary shaft at reduced speed, conventionally, one-fifth of the rotative speed of the meter shaft. Associated with the meter shaft is a contactor and a contact which close a telephone circuit once every revolution of the meter shaft and thus produce a signal in the telephone receiver in the circuit. The second shaft has a similar contactor and a contact which may be used to close the telephone circuit once in every five revolutions of the meter shaft to produce a signal in the receiver.

If the meter is used in a slow running stream the telephone circuit is connected through the first contactor and contact, while in a swift running stream the circuit is connected through the second mentioned contactor and contact. Thus, 25 the operator may readily count the successive signals under either condition since, in a slow current, he receives a signal for each revolution of the meter shaft, while in a swift current there is a signal for only every five revolutions of the shaft.

The above arrangement is objectionable, however, to the extent that it requires that the circuit be set up by the operator in different ways 35 for taking different measurements. This is both time consuming and troublesome for the operator. Furthermore, the necessity for providing for the making and breaking of the circuit connections just mentioned prevents adequate insulation.

According to the present invention, both of the contact mechanisms mentioned are located in the same telephone circuit at all times and are connected up in parallel therein. The low frequency 45 contact mechanism is synchronized with one of the recurrent functions of the high frequency contact mechanism but is given distinctive circuit controlling characteristics so that it produces a slurring or rasping signal in the telephone receiver as distinguished from the sharp click produced by the high frequency contact mechanism. Thus, at high speeds, when their extremely rapid succession renders it impossible to count the clicks produced by the high frequency contact mechanism, it is a simple matter

to count the slurring or rasping signals produced by the low frequency contact mechanism. At low speeds, the clicks of the high frequency contact mechanism may readily be counted. Since the slurring signal is synchronized with every fifth 5 click and is counted as a click, it does not prevent counting the clicks at low speeds, or cause any confusion whatever.

From this it follows that permanent connections can be made since the device is adapted for 10 use in either slow or swift currents without change; adequate insulation can be had; and many of the difficulties and delays heretofore encountered are avoided. The possibility of 15 making permanent connections has the further advantage that a complete interchangeable replacement unit comprising two contact brushes, a support therefor and properly insulated means for connecting the brushes in the telephone circuit, can be provided.

It follows that the performance of the device is improved and the maintenance and manipulative aspects are simplified.

A preferred embodiment of the invention will 25 now be described in connection with the accompanying drawings in which:

Figure 1 is a view partly in section and partly in elevation showing the rotating wheel of the meter, the support, the contact mechanisms and 30 the telephone circuit.

Figure 2 is a diagram of the telephone circuit showing the two contact mechanisms connected in parallel in the circuit.

Figure 3 is an enlarged view of the contact 35 mechanisms shown in Figure 1.

Figure 4 is a plan view thereof with the cap plug removed to render the internal construction visible.

Figure 5 is an enlarged sectional view illustrating the high frequency contact mechanism.

Figure 6 is a similar view of the low frequency contact mechanism.

Figures 7 and 8 are enlarged detail views of the minutely knurled contact surface used to produce 45 the slurring contact in the low frequency contact mechanism.

Each contact mechanism is actually a make and break device. The high frequency contact mechanism is like those heretofore used and produces a make followed so quickly by a break that a single sharp click is produced in the telephone receiver. The low frequency contact mechanism is also basically a make and break device, but the minutely knurled contact surface thereof 55

wipes across a small brush to effect a rapid series of makes and breaks which produces a slurring or rasping noise in the receiver readily distinguished from the sharp click above described.

5 To avoid undue prolixity, the two contactor, contact units will be described as "contact mechanisms," it being understood that they have the make and break characteristics above mentioned, or their equivalent. The essential thing is that 10 two distinguishable audible signals are produced at different frequencies.

Referring to Figure 1, 12 represents the C-shaped yoke or frame in which the rotative wheel structure 13 is mounted. 14 represents a portion 15 of the tail structure which is positioned by the current and which is so formed as to avoid disturbing eddies. 15 is a portion of the hanger by which the meter may be supported. It is common practice to hang the meters on cables 20 or on rods, and since this is conventional, no attempt to illustrate either type of support has been made.

The wheel 13 is an ordinary cone bucket wheel clamped by means of a sleeve 16 and nut 17 to 25 the rotating meter shaft 18. This shaft is sustained at its lower end on a pivot bearing 19 having an inserted hardened bearing point 21 which coacts with a hardened insert 22 in the end of the shaft. The upper end of the shaft 30 26 is mounted in a chambered housing 23 which is removably clamped in frame 12 by means of a clamp screw as usual. The housing 23 carries within its upper portion a radial bearing 24 which centers the upper end of the shaft 18 and a 35 thrust disc 25 for the upper end of shaft 18. Disc 25 is clamped by a screw 26 to the threaded plug 27. The plug 27 forms a removable closure for the upper end of the chamber in the housing 23. The disc 25 may be shifted to present a new 40 area to the upper end of the shaft, so that a new thrust bearing may readily be provided, by releasing the screw 26 and turning the disc 25 slightly with reference to the plug 27.

The housing 23 encloses the upper end of the 45 shaft 18 and that shaft is there formed with a worm 28 which drives a worm wheel 29. This worm wheel is formed at the mid length of a sleeve 30. The worm wheel and sleeve are journaled on a shaft 31 which is supported at its 50 ends by a clip 32, removably mounted in the housing 23 by means of a screw 33.

Between worm 28 and bearing 24 shaft 18 is 55 reduced as indicated at 34 and is there formed with a ridge 35 which serves as a contactor.

55 The sleeve 30 at one side of the worm wheel 29 is provided with a contactor 36 of greater angular extent than the contactor 35, and this contactor 36 is knurled or serrated as indicated at 37. This knurling is indicated on a larger scale in Figures 7 and 8.

The pitch of the worm and the worm wheel are so chosen that the worm wheel 29 and consequently the sleeve 30 make a turn for every 60 five turns of the shaft 18.

65 Threaded into an opening on the side of the housing 23 is an insulating fitting 38. Extending into this fitting is the insulation 39 surrounding the end of a telephone conductor 41. The end of conductor 41 is connected to a metal fitting 42 by an eye 42' formed thereon and is also soldered thereto as indicated at 43. Water resisting insulating material 44, such as a suitable cement, completely surrounds the joint and establishes an insulating water-excluding connection 70 75 between the insulation 39 and the fitting 38.

A screw 45 is threaded through the end of the fitting 38 and into the connector 42. It carries two spring contact brushes, one of which, 46, has a ball-shaped head 47 arranged to coact with the contactor 35 and the other of which, 48, has a ball-shaped head 49 arranged to coact with the contactor 36. The parts are so dimensioned and arranged that the make and break between the brush tip 47 and the contactor 35 are practically momentary, and approximately 10 coincide with the initial contact between the contactor 36 and the brush tip 49, which, as will be readily understood, occurs every fifth revolution of the shaft 18.

Thus, as the shaft 18 turns (and its direction 15 of rotation is fixed by the design of the bucket wheel), there will be produced in the telephone receiver four uniformly timed clicks followed by a slightly longer slurring or rasping sound. If the shaft turns at uniform speed, there will thus 20 be recurrent series of five equally spaced signals of which the fifth is differentiated from the other four. At low speeds, all the signals are counted, each fifth or slurring signal being counted as a click; at high speeds, the clicks become too rapid 25 for the operator to count but the accentuated rasping signals are readily counted.

By differentiating the signals given, it becomes possible to use fixed connections and have both contact brushes active at all times. This permits 30 the use of the unitary coupling represented by the parts 38 to 45 inclusive, together with the attached brushes.

Since the brushes wear or become burned out 35 with use, the construction permits rapid replacement of a unitary spare part which restores all of the parts subject to deterioration.

The telephone circuit is conventional, except that the two contact mechanisms are connected up therein in parallel as appears clearly in the 40 circuit diagram of Figure 2. The cable 39, 41, is connected with the cable 50 by a single-contact separable connector 51. The latter is covered by a removable elastic rubber sheath 52 which practically insulates the entire joint. 45

The cable 50 and a companion cable 54 connected to the frame 12 through the hanger member 15, lead through a double-contact separable connector 55 to the telephone unit which comprises a battery 57 and a telephone receiver 58 connected 50 in circuit as clearly indicated in Figure 1.

These parts are used in the manner common in the art and require no detailed description.

The ratio of 5 to 1 for the two contact mechanisms is selected simply because that is the one 55 used conventionally in the art. For particular cases, other ratios might be adopted.

While the minutely knurled or serrated contact surface 37 on contactor 36 is preferred for producing the slurring or rasping signals, obviously this surface may be roughened in any other suitable manner to produce the desired distinctive signal.

The use of a slurring contact and a single momentary contact are believed to offer the simplest 65 way to differentiate the signals. The important thing is differentiation rather than particular details used to secure it. An important feature of novelty is that both contact mechanisms are in circuit simultaneously and are connected up 70 therein in parallel. Sound differentiation prevents their interfering with each other in the functioning of the device.

What is claimed is:

1. An audible signal device for permitting 75

- counting of the rotations of a shaft comprising a telephone circuit including a telephone receiver and a circuit making contact device driven by the shaft, controlling said circuit and having two distinct types of contact elements, the first type operating to give a sharp momentary make and the second type operating to give a rapidly recurring series of momentary makes, such series being shorter in overall time than twice the interval between the makes of the first type, the frequency of operation of the first type being a multiple of that of the second, and the circuit closing operation of the second coinciding with a circuit closing operation of the first.
- 5 15 2. An audible signal device for permitting counting of the rotations of a shaft which comprises a contactor rotating with said shaft; a second shaft driven by the first shaft and turning at a slower rate, the rate of rotation of the first shaft being a multiple of that of the second; a slurring contactor carried by said second shaft; a pair of individual contacts for said contactors arranged to engage their corresponding contactors once in each revolution of the respective shafts, said contacts engaging their corresponding contactors simultaneously once in each revolution of the second shaft, the relative speed and length of said contactors being such that the second or slurring contactor will engage its co-operating contact for a time interval longer than the time of a single engagement of the first contactor with its co-operating contact but for less than a time interval including two such engagements of the first contactor with its co-operating contact; and a telephone circuit, inclusive of a telephone receiver, in which said first contactor and its corresponding contact and said slurring contactor and its corresponding contact are connected in parallel.
- 10 20 3. The combination defined in claim 2 wherein the contact surface of the slurring contactor is roughened and is a greater angular extent than the contact surface of the first contactor.
